CLAIM

The ornamental design for a locomotive, as shown and described.

DESCRIPTION

1. Locomotive

1.1 : Perspective

1.2 : Enlarged view of a driver's cabin

1.3 : Front

1.4 : Back

1.5 : Side view

1.6 : Top

An industrial design for a locomotive for moving trains or individual wagons along a track; it comprises the following structural elements: a body consisting of a frame accommodating hoods, the driver's cabin with rear-view mirrors, and handrails, the frame installed on locomotive bogies with wheel pairs, and a fuel tank located between the bogies.
